UNITED STATES PATENT OFFICE.

JOHN EMERY LESTER, OF SEATTLE, WASHINGTON.

DESIGN FOR A MANIKIN.

Application filed April 16, 1921. Serial No. 462,040. Term of patent 3½ years.

To all whom it may concern:

Be it known that I, JOHN EMERY LESTER, a citizen of the United States, residing at Seattle, in the county of King and State of Washington, have invented a new, original, and ornamental Design for a Manikin, of which the following is a specification, reference being had to the accompanying drawing, forming a part hereof.

In the drawing, Fig. 1 is a front view and Fig. 2 is a side view of the manikin, showing my new design.

I claim:

The ornamental design for a manikin, as shown.

JOHN EMERY LESTER.
